UNITED STATES PATENT OFFICE

WILLIAM BORCHERT, OF ROCKFORD, ILLINOIS, ASSIGNOR TO THE TAGIT COMPANY,
OF ROCKFORD, ILLINOIS, A CORPORATION OF ILLINOIS

CLIP

Application filed May 29, 1930. Serial No. 457,009.

This invention relates to clips and has for its object the provision of an improved clip especially adapted for clasping and holding garments on wire hangers.

Because of their economy, wire hangers are extensively used by cleaning establishments and in homes for hanging garments of various descriptions. They are objectionable, however, for hanging dresses and gowns because of the tendency of such garments to slip off the hangers, particularly when being handled; and it is not infrequent that costly gowns are soiled or sometimes damaged by falling from hangers while they are being handled in cleaning establishments or when being delivered to the customer. When delivery is made with the garment suspended on the wire hangers as for example when the hanger is hung within the closed body of a motor vehicle, the vibration and jostling frequently causes the garment to slip to one side and fall from the hanger. Under these circumstances the garment will be wrinkled and sometimes soiled to the extent of damage to the material, with the result that it becomes necessary to either reclean the garment or sometimes replace it or its value.

My invention aims to remedy these conditions by the provision of an improved clip designed to be quickly and easily passed over the shoulder piece of a garment on a wire hanger and pressed or pinched between the fingers to securely hold it and the garment from displacement. According to my invention the clip is so formed and constructed that it will not mar, spot or discolor even the finest of silks, velvets, chiffons and other fabrics. The clip may be just as readily removed for removal of the garment and it may be used again if desired.

Another feature of my improved clip is that it may be produced at an exceptionally low cost so that it is a negligible item of expense in comparison with the benefits following from its use in cleaning establish-

ments and other places and in preventing injury to garments when making deliveries.

Other objects and attendant advantages will be apparent as the invention becomes better understood by reference to the following description when considered in connection with the accompanying drawing in which—

Figure 1 is a perspective view of a clip embodying my invention;

Fig. 2 shows clips of this kind applied to a garment on a wire hanger;

Fig. 3 is a view illustrating diagrammatically a preferred method of making the clip;

Figs. 4, 5 and 6 are cross-sections taken on the line 4—4, 5—5, 6—6 respectively of Fig. 3; and

Fig. 7 shows the manner in which the clips are cut from a strip.

My invention contemplates, briefly stated, the provision of a clip 8 of general V-shape formed of a metallic body and coated with a suitable sheath or covering of such characteristics as not to be harmful or injurious to the fine materials found in dresses and gowns. The body is preferably of a soft metal such for example as zinc, lead, or dead-soft iron, or some combination of a low-priced metal having the characteristics of the metals referred to. The covering may be of paper, or fabric, or some composition which will not mar or spot the fine materials of the garments referred to. I prefer to use a fabric covering because of the durability of such material and the fact that it provides the desired protection against rust spots in the use of the clips. The clip, so constructed of these materials, may be quickly and easily clasped over the shoulder piece of a garment on a wire hanger simply by pressing the sides of the clip together with the fingers. Clips so applied to both shoulder pieces will retain the garment from slipping from the inclined supporting wires of the hanger and will serve in a practical and satisfactory manner the purposes intended.

With the foregoing in mind my improved clip may be constructed in various ways. In the embodiment here shown for purposes of illustration a continuous strip is formed from which the individual clips are severed by a cutting operation. Each clip is then formed to the finished shape.

As shown in Fig. 3 the body 9 is normally a flat metallic strip of the character above described. In the course of making the clip with automatic machinery this body strip is super-imposed on a covering strip 10 of paper or other material of greater width so that its side portions protrude beyond the body strip as shown. The side flange portions 11 of the body strip as well as the side portions 12 of the covering strip are folded upwardly as clearly shown in Figs. 3 and 4 and the protruding end portions 10 are then folded inwardly over the inner sides of the body portions 11 as shown in Fig. 5. The upstanding body portions 11 thus covered are bent inwardly and pressed against the main body portion making a flat multi-ply strip as shown in Fig. 6 and a confining end locking the ends of the covering strip from pulling out or being displaced. In this manner the metallic body is entirely covered and protected so that it does not come in contact with the garment when the clip is applied. The strip thus formed is then severed at uniformly spaced points as for example as shown in Fig. 7 by cutting at 13. The cutting die may be shaped to round or bevel the corners as shown or this beveling may be done in a previous operation as at 14. In the latter instance the beveling notches 14 may be used for the engagement of feed elements for advancing the strip lengthwise the desired distance in the machine for the cutting operation. The bending or folding of the body and the covering strips in the manner described may be accomplished by any suitable means. For example, these operations may be performed continuously and progressively in the manner illustrated in Fig. 3. The individual clips will then be formed to the shape shown in Fig. 1, ready for use preferably by bending medially intermediate their ends and by further bending the ends outwardly.

It will be seen from the foregoing description that I have provided a clip of the pinch-on type, that is, one which is passed over the garment and then pinched between the fingers to grip the garment and hold it on the hanger, a clip of this type being particularly well adapted to use with wire hangers. The narrowness of the clips prevents wrinkling of the material at the points where the same are applied and the fact that the metal in the clip is completely covered with the cloth or other sheathing eliminates the danger of runs in delicate materials. The form of the clip with diverging fingers is desirable be-

cause with such a wide mouth the clip can be fastened onto garments of different thicknesses with equal facility. The bending outwardly of the ends of the fingers is provided primarily to keep the ends from coming in contact with the delicate materials of certain garments, it being found that even a slight burr is apt to cause a run. With the clip formed as herein illustrated and described, the garment is protected against any damage while held by the clip on the hanger.

While I have illustrated but a single embodiment it should be understood that my invention contemplates the use of various materials for the body and the covering of the clip as well as changes in the detailed construction of the clip without departing from the spirit and scope of the invention as specified in the appended claims, in which—

I claim:

1. A clip formed of a flat metal body strip and a non-metallic covering strip of greater width than the body strip, the covering strip having its side portions turned inwardly over the side portions of the body strip, and the said side portions of the body strip thus covered being bent inwardly upon the main body portion of the body strip, and the covered body strip being bent medially between its ends to provide diverging fingers.

2. A clip of the character described comprising a body member of soft metal in strip form, a sheath of material having characteristics similar to paper or fabric, said sheath being arranged to cover one side of the body strip and to be folded over the edges and against the opposite side thereof, the covered side portions of the body strip being turned inwardly and folded down to clamp and retain the edges of the sheath, and the covered body strip being bent upon itself to provide opposed fingers adapted to be clasped onto the shoulder pieces of a garment hung on a wire hanger for retaining the garment thereon.

3. A clip of the character described comprising a flat metal body strip, and a sheathing therefor, the latter having its side portions turn inwardly over the longitudinal edges of the body strip, and the body strip being bent lengthwise so as to bring the folded side portions of the sheathing on the inside and held in place by reason of the bending of the body strip, the clip thus formed being bent upon itself to provide diverging fingers for gripping a garment on a hanger when the said fingers are pressed together.

4. A hanger clip for use in holding garments on wire hangers, the same comprising an elongated body strip of readily conformable metal bent at the middle into a V shape, the metal being of such thinness and softness to conform itself at the bent portion to the wire of the hanger when the clip is placed over a garment thereon and its diverging ends

pressed together and being of sufficient length, when folded, to not only grip the hanger firmly at the bend but also grip the garment material between the pressed-together ends of the clip, the metal of the strip being furthermore substantially non-resilient so that the pressed-together ends will stay together and frictionally grip the garment material therebetween, and a sheath substantially completely covering the strip for protection of the garment material from contact with the metal of said strip, said sheath being of readily conformable material to adapt itself to the shape to which the strip is pressed.

15 In witness of the foregoing I affix my signature.

WILLIAM BORCHERT.
